SEAL INDICATOR FOR PUMPS

De Mont G. Miller, Los Angeles, Calif.

Application December 13, 1938, Serial No. 245,425

7 Claims. (Cl. 177—311)

This invention relates generally to deep well turbine pumps and more particularly to devices for indicating the axial adjustment of the impeller.

5 An object of this invention is to provide a seal indicator, which, in its association with a turbine or centrifugal pump, indicates with absolute accuracy, engagement of the pump impeller with its seal so as to enable proper adjustment of the 10 impeller to be made in order to obtain maximum pumping efficiency by obviating slippage of water around the impeller.

A further object of the invention is to provide a seal indicator of the above described character 15 by which an accurate indication can be obtained, irrespective of a worn condition of the seal, so that the latter need not be replaced when worn sufficiently to cause a loose fit with the attending loss of efficiency, but instead a new setting or 20 adjustment of the impeller made to again establish the proper relationship of the impeller to the seal for maximum pumping efficiency, thus effecting a considerable saving in the maintenance of the pump.

25 Still another object of the invention is to provide a seal indicator which is structurally characterized in a manner to enable it to be installed in a pump without modifying the construction of the pump, so as to enable the indicator to be 30 readily applied to any existing pump.

With these and other objects in view, the invention consists in the combinations, arrangements and functional relationships of elements set forth in the following specification and particularly pointed out in the appended claims.

35 In the accompanying drawing,

Figure 1 is a vertical sectional view illustrating a deep well turbine pump with one form of seal indicator embodying this invention applied thereto;

40 Figure 2 is an enlarged detail sectional view of the seal indicator applied to the pump;

Figure 3 is a longitudinal sectional view taken on the line 3—3 of Figure 2;

45 Figure 4 is a transverse sectional view taken on the line 4—4 of Figure 2.

In deep well centrifugal or turbine pumps as at present constructed, a loss of efficiency is mainly caused by slippage of water around the 50 impellers.

In those pumps having enclosed impellers with side seals a loss in efficiency results from loose fits of parts in manufacture; subsequent wear from abrasion by sand; or oxidation of the 55 metals. In any case, necessary repairs can be

made only by disassembling the pump and installing new seal rings.

In those pumps having enclosed or open bottom impellers and bottom seal rings, slippage of water is controlled by first attempting to set the 5 bottoms of the impellers in contact with the seals. However, due to expansion and elasticity of metals, it is impossible to determine the exact setting of the impellers under operating conditions, from the surface of the well, and is exceedingly difficult with pump settings over one hundred feet.

Furthermore, in a multi-stage pump assembly, 15 the impellers are either keyed or wedged on the drive shaft, with imperfect spacing of the impellers in a stock pump so that one impeller may seat as much as a sixteenth of an inch before another. In pumps using bottom seals of rubber or hard metals, perfect seals on all impellers is very seldom accomplished.

In carrying this invention into practice, the multi-stage deep well pump illustrated generally in Figure 1 is provided with bottom seals 10 in the form of rings. These seals are preferably constructed of materials softer than the impellers, 25 such as bronze or lead, which latter, although relatively soft, has been found highly efficient and resistant to wear. Furthermore, materials other than metals, such as resilient rubber, can 30 be used.

In constructing the seals 10 of lead, they are reinforced with steel wire 11 so that the rings will not readily become deformed if abused. In existing pumps, these rings will merely be 35 substituted for the original seal rings so as to seat in the bowls 12 of the pump and co-act with the impellers 13 in the same manner as the original rings.

One of the rings 10 is utilized in conjunction with an indicating device embodied in this invention and comprising a switch S composed of a housing or support 15 in the form of a metallic cylinder having its ends sealed to provide a fluid-tight chamber 16, by means of elastic rubber plugs 17 and 18 which are vulcanized in place.

40 The housing 15 also constitutes a fixed electrical contact which is adapted to co-act with a movable contact 19 in the form of a metal disk of somewhat smaller diameter than the internal 45 diameter of the housing. The contact 19 is fixed to one end of a rod 20 the other insulated end of which passes through and is vulcanized fluid-tight in a central opening 21 in the plug 17 so as to co-act with the latter in providing an elec- 50

trically insulated mounting means for the contact.

The contact 19 is thus mounted to normally occupy the open-circuit position shown in Figure 2, wherein it is clear of the housing 15, yet is adapted to be tilted in any direction to occupy a closed-circuit position in engagement with the housing, by the functioning of the plug 17 as an elastic fulcrum.

10 The rod 20 projects from the plug 17 and has fixed thereto exteriorly of the housing a head 22 which broadly constitutes an actuating portion of the switch S and is preferably constructed of lead, (as is the wear ring 10) or of some other material having approximately the same wearing quality as the ring, so as to wear at substantially the same rate as the ring, when subjected to the same conditions as the ring, all for a purpose to be fully described in the operation of the invention.

20 A suitable indicator which may be audible, such as a bell or buzzer, or visual, such as a lamp or meter, as shown at 25, is conveniently located at the surface of the well, and is in a single wire circuit through a conductor 26 grounded to the pump, the indicator and a battery 27 being in series with the conductor.

30 The conductor 26 extends through the well casing 28, and is adapted to be connected to the contact 19 of the switch S when associated with the pump as shown in Figure 1. For this purpose the conductor 26 is vulcanized in an opening in the plug 18 and passes freely through a slot 29 in the contact. The conductor is wound freely 35 around the uninsulated end of the rod 20 so as not to interfere with the free tilting movement thereof, and is permanently fixed at 30 to the rod by soldering or other means.

40 The housing 15 is externally threaded at 31, and is applied to the pump, preferably at the bowl 12 of the first stage of the pump by being screwed into an opening 32 in the wall of the bowl, as shown in Figure 1, so as to dispose the actuating head 22 in the bowl at a location eccentrically of the impeller axis, and in the path of rotation of any part of the bottom of the impeller when lowered to a predetermined position by axial adjustment of the impeller assembly as a unit from the top of the pump by a suitable nut 45 33 provided for this purpose on the upper end of the impeller shaft 34, all to the end of effecting tilting movement of the head by the impeller in a wiping motion across the head, to move the contact 19 to its closed-circuit position, as will 50 be fully described in the following operation.

55 Let it be assumed that the seal indicator is installed as shown in Figure 1 and that the impeller assembly is to be adjusted to obtain the proper bottom seal.

60 The impeller assembly is lowered to rest its weight on one or more seals, depending on the accuracy of the assembly, in which lowered position the actuating head 22 will be disposed in the path of rotation of the bottom shroud or any 65 part of the open bottom of the impeller, as the case may be.

70 Upon rotation of the impeller assembly, the head 22 will be engaged and tilted by the respective impeller in a wiping motion perpendicular to the path of rotation as shown in Figure 3, and will thus cause the contact 19 to engage the housing 15 and close the circuit including the indicator 25.

75 The indicator is thus activated to indicate that the impeller assembly has been lowered suf-

ficiently to engage the impeller with its seal 10. The operation of the pump is continued, and will wear the seal 10 and the head 22 correspondingly until the impeller no longer tilts the head, whereupon the latter will disengage the housing 15 and the circuit will be disrupted to render the indicator inactive.

80 Should the efficiency of the pump decrease due to abrasive wear from sand or wear from any other cause, a further lowering adjustment of the impeller assembly is made, until upon again operating the pump, the head 22 will be tilted to again close the circuit and activate the indicator 25 to indicate that the impeller is in engagement with the seal 10.

85 It will be clear that due to the similarity of materials from which the seal 10 and head 22 are constructed, and to the fact that they are both subjected to similar conditions in the pump they will wear substantially uniformly so that the head 22 will at all times be an accurate gage.

90 Thus whenever a new setting of the impeller assembly is made and the indicator is activated, it is assured that the impeller is actually in engagement with its seal. Wear on the seal is thereby automatically compensated for to insure that the indicator will give an accurate indication irrespective of the extent to which the seal 10 is worn, thus making it unnecessary to disassemble the pump and replace worn seals in order to be enabled to accurately determine the axial relationship of the impeller to its seal, as is required with indicators of the prior art.

95 It will be manifest that the invention is applicable to function with equal efficiency in pumps having open bottom impellers, as, in such an installation, the head 22 will be engaged by the bottom edges of the vanes during rotation of the impeller assembly.

100 What is claimed is:

1. In a deep well turbine pump having a bottom seal member, an impeller, means to vertically adjust the impeller relative to the seal member, a signal circuit including a switch; means for actuating the switch; said means including an actuating portion composed of a material having substantially the same wearing quality as the bottom sealing member and means mounting said actuating means in a position for said portion thereof to be moved by the impeller with a wiping motion of its lower surface in response to rotation of the impeller, so as to actuate the switch when the impeller rotates in contact with the seal member and actuating means.

105 2. In a deep well turbine pump having a bottom seal member, an impeller, means to vertically adjust the impeller relative to the seal member, a signal circuit including a switch; means for actuating the switch; said means including an actuating portion composed of a material having substantially the same wearing quality as the bottom sealing member; and means mounting said actuating means from the pump bowl with said actuating portion located eccentrically of the impeller axis, and for switch actuating movement by the impeller with a wiping motion of its lower surface as the impeller is rotated in contact with the seal member and actuating means.

110 3. In a deep well turbine pump having a bottom seal member, an impeller, means to vertically adjust the impeller relative to the seal member, a signal circuit including a switch; means for actuating the switch; said means including an actuating portion composed of a material hav-

ing substantially the same wearing quality as the bottom sealing member; and means tiltably mounting said actuating means in a position for said actuating portion thereof to be tilted by a wiping motion of the impeller during its rotation, so as to actuate the switch when the impeller rotates in contact with the seal member and actuating means.

4. In a deep well turbine pump, an impeller; a bottom seal member; means to vertically adjust the impeller relative to the seal member; indicator activating means of substantially the same wearing quality as the seal member; and means movably mounting said activating means in a position for the latter to be moved by the impeller with a wiping motion of its lower surface in response to rotation of the impeller, for activation of an indicator when the impeller rotates in contact with the seal member and activating means.

5. In a deep well turbine pump, an impeller; a bottom seal member; means to vertically adjust the impeller relative to the seal member; indicator activating means having an actuating portion of substantially the same wearing quality as the seal member; and means mounting said activating means from the pump bowl with said portion located eccentrically of the impeller axis for movement by a wiping motion of the impeller when rotating, to activate an indi-

cator when the impeller contacts the seal member.

6. In a deep well turbine pump, an impeller; a bottom seal member; means to vertically adjust the impeller relative to the seal member; indicator activating means having an actuating portion of substantially the same wearing quality as the seal member; and means tiltably mounting said activating means with said portion thereof in a position to be tilted by a wiping motion of the impeller when rotating, for activation of an indicator upon contact of the impeller with the seal member.

7. A seal indicator for deep well turbine pumps having a rotary impeller unit vertically adjustable with respect to a seal member, which comprises: a housing adapted to be supported by a pump bowl; a contact; means movably mounting and sealing said contact in the housing to normally occupy one position; and means of substantially the same wearing quality as the seal member; said means being connected to said contact and disposed exteriorly of the housing for engagement by a part of the impeller unit upon a predetermined vertical displacement thereof, to move the contact to another position by a wiping motion of said part upon the contact during rotation of the unit.
